SUPERVISORY UNIT FOR BURGLAR ALARM SYSTEM

Clifford Lee Loudon, La Jolla, Calif., and William E. Riker, Cold Spring Harbor, N. Y., assignors to Holmes Electric Protective Company, New York, N. Y., a corporation of New York

Application March 21, 1955, Serial No. 495,486

14 Claims. (Cl. 340—258)

The present invention relates to a supervisory unit for use with a burglar alarm system, and in particular, to a supervisory unit for use with a burglar alarm system which detects the presence of an intruder in the protected area as a result of the disturbance of a complex pattern of ultrasonic sound waves. Most burglar alarm systems operate on the change of or interruption in a normal energy flow caused by the presence or entrance of an intruder. Therefore, it is comparatively simple to supervise the effectiveness of such a system since it is merely necessary to determine whether or not there is a normal flow of energy in the system. However, the system with which the present invention is to be used is a space type which operates upon the conversion of energy rather than the interruption of energy flow. In this system ultrasonic waves at a fixed frequency are propagated in the enclosure to be protected thereby establishing a standing wave pattern. A microphone also located in the enclosure picks up these waves and converts the sound energy to electrical energy. If these waves are disturbed the amount of energy and the frequency of the waves change and the alarm will be actuated.

It can be seen from this that this type of system is far more difficult to supervise than the system initially described above since it is difficult to test the energy conversion characteristics of the system without producing an erroneous alarm.

It is an object of the present invention to provide a supervisory unit for a space type burglar alarm system which provides a periodic check of the operation of the system.

It is another object of the present invention to provide a supervisory unit which periodically tests the operability of its associated burglar alarm system.

It is another object of the present invention to provide a supervisory unit for a burglar alarm system which is periodically tested automatically and which may be tested, when desired, from a remote point.

It is another object of the present invention to provide a supervisory unit for a space type burglar alarm system.

It is another object of the present invention to provide a supervisory unit for periodically checking the operability of a space type burglar alarm system which also provides circuits for detecting malfunctioning of the supervisory unit.

It is a further object of the present invention to provide a supervisory unit for checking the operability of a space type burglar alarm system by simulating the presence of an intruder in the protected enclosure.

It is still another object of the present invention to provide a supervisory unit for automatically checking the operability of a space type burglar alarm system which upon detecting a failure in the system sends an indication to the central office which is different from the indication supplied when an intruder is detected in the enclosure.

It is still another object of the present invention to

provide a supervisory unit for automatically checking the operability of a space type burglar alarm system which provides for automatic periodic testing that is initiated at the protected enclosure and also provides for the initiation of tests from a remote point, the two test circuits being independent of one another.

In the drawings:

Fig. 1 is a block diagram showing the system in which the present invention is to be used;

10 Fig. 2 is a circuit diagram of the supervisory unit of the present invention;

Fig. 3 is a circuit diagram of the supervisory unit showing the position of the relays during the period of a local test.

15 Referring to Fig. 1, ultrasonic waves at a frequency of approximately 17 kc./s. are propagated, in the enclosure to be protected, by means of a loudspeaker 10. The transmitter unit 12 which supplies electrical energy of the proper frequency to the loudspeaker 10 receives its power from a power supply 16 over the line 14. The ultrasonic waves which are emitted by the speaker 10 undergo a complex process of reflection and absorption which sets up a standing wave pattern within the enclosure. These standing waves are picked up by the microphone 18 and converted to electrical energy which is fed to the receiver unit 20. If there is no disturbance in the room the receiver unit 20 will have supplied to it an unmodulated 17 kc. wave. The receiver which is the subject of copending application Ser. No. 495,484, filed by Loudon and Riker, on March 21, 1955, detects any modulation of the 17 kc. wave. If the wave is unmodulated there will be no output from the receiver unit. If, however, an intruder enters the enclosure his movements will both amplitude modulate and frequency modulate the 17 kc. carrier. Both portions of this wave will be detected by the receiver unit thereby producing an A.C. output which will be fed over the lines 22 and 24 to the supervisory unit 26. Upon receipt of such a signal the supervisory unit will sound an alarm in the central office; connection between the supervisory unit and the central office being over lines 28 and 40. The receiver unit 20 and supervisory unit 26 receive power from the main power supply unit 16 over lines 32 and 34 and 36 and 38 respectively. Another output of the supervisory unit 26 is connected to the transmitter unit 12 over the line 30 for reasons to be explained further on in the specification.

40 The operation of the supervisory unit will now be explained with reference being made to Figs. 2 and 3. As previously explained, the supervisory unit is connected to the central office by means of the lines 28 and 40. The central office circuit is essentially the same as shown in the Miranda Patent No. 1,881,832, issued October 11, 1932. These lines are connected to a voltage supply 41 at the central office which normally maintains a direct current, of say 12 milliamperes, in a circuit in the supervisory unit which consists of the signaling device 42, line 44, changer magnet 46, the front coil 48b of the differential relay 48, line 50, line 52, the forward contact 54a of the relay 54, the armature 54b, line 56, the front contact 58a and armature 58b of the relay 58, line 60, the other coil 48a, shunt 48e of the differential relay 48, the line 62, the resistor 64, the line 66, resistor 68, line 70 and line 28. The 12 milliamperes flowing through this circuit are insufficient to cause actuation of the signaling device 42. Also this current indicates at the central office that normal conditions prevail, this being shown by the fact that the pointer 43 of the meter 45 remains centered. This current, as indicated above, flows through both the coils 48a and 48b of the differential relay 48 and causes a balance to be established in

the relay such that the armature 48d is not engaging the contact 48c.

The above conditions as already indicated prevail under normal operation. If an intruder enters the building or for some other reason a signal occurs in the output of the receiver unit 20, a signal is developed in the transformer winding 72. The signal is rectified by the rectifier 74 and filtered by the condenser 76. The resulting direct current is applied to the relay 78 thereby actuating the relay. Upon actuation the relay pulls the armatures 78a and 78b into engagement with the contacts 78c and 78d respectively. Upon the engagement of the armature 78a with contact 78c, a portion of the circuit in which the 12 milliamperes are normally flowing is shorted. The current from the central office now flows from line 40 through the signaling device 42, line 44, changer magnet relay 46, the coil 48b of the differential relay 48, line 50, line 80, contact 82b of the switch 82 which is normally closed, line 84, armature 78a, contact 78c, line 86, line 85 and back to the central office over line 28. Therefore, the coil 48a of the differential relay 48, resistor 64 and resistor 68 have been shunted.

The elimination of these elements from the circuit causes an increase in current to, say 17 milliamperes. At the central office the pointer 43 is caused to move by the increased current and touches one of the contacts 47. This energizes the relay 49 which drops the armature 51 onto the contact 53 which energizes the alarm 55 thereby indicating at the central office the presence of the intruder. Since the current flow through the coil 48a of the differential relay 48 has been interrupted, the armature 48d is caused to engage the contact 48c. This circuit is in parallel with the armature 78a and contact 78c. The increased current will now be maintained even though signals may no longer be received from the receiver unit 20. The system may be reset by someone investigating the alarm or by opening the entire central office circuit at the central office.

In providing supervisory control of the overall system, it has been found convenient to test the operation of the relay 78 as an indication of proper functioning of the system. These tests are made automatically at 30-second intervals and also may be made at any time from the central office. During these tests the normal signal emitted by the transmitter and loudspeaker is altered to simulate the signal that would be produced by an intruder moving through the room. At the same time that the normal signal is disrupted, the contacts of relay 78 are disconnected from the central office circuit. The modulated signal is picked up by the microphone 18 and amplified, detected and rectified by the receiver unit 20. This signal is applied to the relay 78 again causing it to attract the armatures 78a and 78b. Upon closure of the armature 78b and contact 78d the condenser 87 in the grid circuit of the tube 88 begins to receive a charge from a power supply connected to the line 90. The conduction of the tube 88 maintains the armatures 92a and 54b of the relays 92 and 54 respectively in the positions shown in the Figure 3. It will be noted that the armature 54b and contact 54a of the relay 54 are in the central office circuit previously described. The relay 54 is chosen so that it will remain actuated by a current which is somewhat less than full plate current of the tube 88. Therefore, as the voltage on the grid of the tube 88 decreases as a result of the discharge of the condenser 87 through the resistor 94 in the interval between test periods, the current in the plate circuit will not decrease sufficiently to cause de-energization of the relay 54 unless the condenser 87 is allowed to discharge, without recharging, for several test intervals. If the charge on the condenser does fall sufficiently due to malfunctioning of the relay 78 for several test periods, the current through the relay 54 will be decreased sufficiently to allow the armature 54b to assume the non-operative position. This will open the contacts 54a and 54b in the central office circuit and

therefore interrupt the 12 milliamperes current indicating that the system is malfunctioning.

The automatic tests are controlled by the operation of the motor 96. The motor drives the two cam wheels 82 and 98 through the gear train 99 at a rate determined by the number of test operations desired per minute. As pointed out above, the present system operates at two tests per minute and therefore the cams are driven at one revolution per minute. Each cam has two notches in its circumference spaced approximately 180 degrees apart. Cam followers 82a and 98a are positioned so as to ride on the circumference of the cams 82 and 98 respectively. Each follower operates a microswitch which controls the opening and closing of the contacts 82b and 98b. The microswitch associated with cam 82 is normally closed and the microswitch associated with the cam 98 is normally open. When the cams have been rotated so that the cam followers fall into the notches on their respective cams a test cycle which lasts about two seconds is started.

Referring to Fig. 3, when the cam follower 98a falls into the notch on the cam 98, a circuit is closed which includes the line 100, which is connected to a power supply, the switch contact 98b, line 102, the line 30 to the transmitter unit and the coil of the relay 104 in the transmitter unit. This energizes the relay which attracts its armature 104a and disengages it from the contact 104b. The opening of the armature and contact adds the resistor 106 to the plate circuit of the transmitter unit's oscillator tube. This alters the frequency of oscillation of the transmitter oscillator in a manner which simulates the presence of an intruder in the enclosure. At the same time that this is occurring, the cam follower 82a has entered the notch on the cam 82 thereby opening its associated microswitch. This breaks the line between the relay armature 78a and the central office so that if the receiver unit detects the change in frequency an alarm will not be sounded in the central office. Since the test lasts for only about 2 seconds, the protection afforded by the system is not materially decreased. However, actuation of the relay 78 will maintain the condenser 87 sufficiently charged through armature 78b and contact 78d to keep the relay 54 actuated; thereby maintaining the central office circuit closed, which is the normal condition.

A second supervisory circuit is provided to detect a failure in the first supervisory circuit just explained. The remote possibility exists that relay 54 may be abnormally held operated and the supervision afforded by the first supervisory circuit will consequently be destroyed, since regardless of whether or not the relay 78 is operating the line to the central office cannot be opened. To guard against such a possibility, a second supervisory circuit is provided which is very similar in operation to that of the first circuit. The relay 92 which is connected in the plate circuit of the tube 88 in series with the relay 54 depends for its operation upon the normal rise and fall of plate current in the tube 88. This relay is adjusted so that it releases its armature 92a just before the plate current in the tube 88 reaches its normal minimum. When the armature is released it engages the contact 92b connecting the condenser 108 to the line 90. This charges the condenser which is in the grid circuit of the tube 110 and thereby maintains the plate current of this tube at a sufficient value to maintain the relay 58 actuated. If the relay 92 is not released for several successive test periods, the capacitor 108 will discharge sufficiently through the resistor 112 to cause the plate current of the tube 110 to fall to a value which will allow the armature 58b to be released. This will open the central office circuit thereby indicating a failure in the supervisory circuit. Therefore, as a result of this second circuit, even if the relay 54, tube 88 or the associated circuits are not operating properly, the second supervisory circuit will indicate malfunctioning.

It will be noted that the signals received at the central

office due to the presence of an intruder are different from those which are due to a malfunctioning of the circuit. When an intruder is detected, the current flowing in the central office circuit is increased to a value which will set off the alarm in the central office. If malfunctioning is detected the central office circuit is open and all current flow in the circuit is terminated.

Provision is also made in the improved system of the present invention for a test to be conducted from the central office. The supervision afforded by the automatic tests is not entirely complete. If both of the relays 54 and 92 are abnormally held operated, the alarm system can become inoperative without the central office being aware of the fact. Therefore, central office tests are conducted at the beginning of and at least once during each protected period. In order that the central office test will be effective regardless of the operation of the aforementioned relays, the central office test is independent of these units, and operates in the same manner in which the system will operate if an intruder is present. In order to make such a test from the central office, two conditions must be met. First, a test signal must be initiated by the transmitter unit 12 and, second, the contacts 78a and 78c of the relay 78 must be connected to the central office regardless of the position of the cam follower 82a. To initiate a test at the central office, the current in the central office circuit is increased momentarily by moving the contact 57 to cause it to engage contact 59. This puts the high voltage battery 61 in the line. This increase of current is sufficient to cause the stepping relay 46 to move the insulator wheel 46a to such a position that the contacts 46b and 46c are allowed to touch each other. This bypasses the resistor 64 in the central office circuit thereby decreasing the resistance of the circuit. The decreased resistance will allow the current in the central office circuit to rise to a value of 15 milliamperes. This is the first phase of the central office test and is utilized to determine if the stepping relay and the central office circuit are in proper operating condition. Also this test is used to calibrate the contact making meter 45 of the central office equipment.

After this initial phase has been completed, the current in the central office circuit is again briefly increased to a value which is sufficient to cause the relay 46 to move the insulating ring 46a into its third position. Under these circumstances, the contacts 46b and 46c are again opened but the contacts 46d and 46e are closed. This connects the resistor 64 back into the central office circuit but now the relay 114 is connected in parallel with this resistor. Actuation of the relay attracts the armatures 114a and 114b thereby bypassing the microswitch which is actuated by the cam follower 98a. This energizes the solenoid 104 in the transmitter unit and causes the transmitter to emit a signal. The operation of the armature 114a bypasses the microswitch actuated by the cam follower 82a and insures that the armature 78a and contact 78c are in the central office circuit. If this system is in proper operating condition, an intruder signal is received in the central office. When a signal is received the current in the central office circuit is again briefly increased. This actuates the changer magnet for a third time and causes the insulating ring to be returned to the position shown in Figure 2.

As this invention may be embodied in several forms without departing from the spirit or essential characteristics thereof, the present embodiment is therefore illustrative and not restrictive, since the scope of the invention is defined by the appended claims rather than by the description preceding them, and all changes that fall within the metes and bounds of the claims or that form their functional as well as conjointly cooperative equivalents, are therefore intended to be embraced by those claims.

We claim:

1. A supervisory circuit for use with a burglar alarm

system which detects the presence of an intruder by responding to the disturbance of a standing wave pattern of ultrasonic waves which comprises a first circuit connected to a remote location, said first circuit carrying a predetermined current, a second circuit connected across a portion of said first circuit, a normally open switch in said second circuit, means actuated during a disturbance of the standing wave pattern to close said switch, means for disturbing the standing wave pattern during predetermined periods, means for opening said second circuit during said periods to prevent alarm operation, and means, including said first mentioned means, responsive to a malfunctioning of the alarm system to decrease the current in said first circuit to cause alarm operation.

2. A supervisory circuit for use with a burglar alarm system which detects the presence of an intruder by responding to the disturbance of a standing wave pattern of ultrasonic waves which comprises a first circuit connected to a remote location, a first normally closed switch connected in said first circuit and when open causing an alarm, said first circuit carrying a predetermined normal current, a second circuit including a normally open switch connected across a portion of said first circuit and when closed shunting said portion of said first circuit to cause an alarm to be given, means operated during a disturbance of the standing wave pattern to close said normally open switch to give an alarm, means for disturbing the standing wave pattern during predetermined periods, means for opening said second circuit during said periods, and means responsive to the failure of operation of said first mentioned means during several of said predetermined periods to open said first switch to cause an alarm.

3. A supervisory circuit for use with a burglar alarm system which detects the presence of an intruder by responding to the disturbance of a standing wave pattern of ultrasonic waves which comprises a first circuit connected to a remote location, said first circuit comprising at least a first normally closed switch and an impedance, a second circuit comprising a second normally closed switch and a normally open switch, said second circuit connected across a portion of said first circuit including said impedance, means operated during a disturbance of the standing wave pattern to close said normally open switch and shunt said impedance, means for periodically disturbing the standing wave pattern for predetermined periods, means for opening said second normally closed switch during said periods and means responsive to a failure of said first mentioned means to operate for several of said predetermined periods to open said first normally closed switch.

4. A supervisory circuit for use with a burglar alarm system which detects the presence of an intruder by responding to the disturbance of a standing wave pattern of ultrasonic waves which comprises a first circuit connected to a remote location, said first circuit carrying a predetermined current, a second circuit shorting a portion of said first circuit, a normally open switch in said second circuit, means actuated during a disturbance of the standing wave pattern to close said switch, automatic means for disturbing the standing wave pattern during predetermined periods, means for opening said second circuit during said period, means responsive to a signal initiated at the remote location for disturbing the standing wave pattern and means also responsive to said signal and in parallel with said third mentioned means so as to close said second circuit.

5. A supervisory circuit for use with a burglar alarm system which detects the presence of an intruder by responding to the disturbance of a standing wave pattern of ultrasonic waves which comprises a first circuit connected to a remote location, said first circuit comprising at least a first normally closed switch and an impedance, a second circuit comprising a second normally closed switch and a normally open switch, said second circuit connected

across a portion of said first circuit including said impedance, means operated during a disturbance of the standing wave pattern to close said normally open switch, means for periodically disturbing the standing wave pattern for predetermined periods, means for opening said second normally closed switch during said period, means responsive to a signal initiated on said first circuit at the remote location for short circuiting at least part of said impedance, a relay, said last mentioned means being responsive to a second signal initiated at the remote location for opening the short circuit across the impedance and for connecting said relay across at least part of the impedance thereby energizing said relay, means responsive to the energization of said relay for disturbing the standing wave pattern and means also responsive to the energization of said relay for short circuiting said second normally closed switch.

6. A supervisory circuit for use with a burglar alarm system which detects the presence of an intruder by responding to the disturbance of a standing wave pattern of ultrasonic waves which comprises a first circuit connected to a remote location, said first circuit comprising at least a first normally closed switch and an impedance, a second circuit comprising a second normally closed switch and a normally open switch, said second circuit connected across a portion of said first circuit including said impedance, means operated during a disturbance of the standing wave pattern to close said normally open switch, means for periodically disturbing the standing wave pattern for predetermined periods, means for opening said second normally closed switch during said periods, an energy storing device, means responsive to the operation of said first mentioned means for supplying energy to said energy storing device, means for continuously dissipating the energy in said energy storing device and means actuated when the energy stored in the energy storing device falls below a predetermined level for opening said first normally closed switch.

7. A supervisory circuit for use with a burglar alarm system which detects the presence of an intruder by responding to the disturbance of a standing wave pattern of ultrasonic waves which comprises a first circuit connected to a remote location, said first circuit comprising at least a first normally closed switch and an impedance, a second circuit comprising a second normally closed switch and a normally open switch, said second circuit connected across a portion of said first circuit including said impedance, means operated during a disturbance of the standing wave pattern to close said normally open switch, means for periodically disturbing the standing wave pattern for predetermined periods, means for opening said second normally closed switch during said periods, an energy storing device, means responsive to the operation of said first mentioned means for supplying energy to said energy storing device, means for continuously dissipating the energy in said energy storing device, the rate of dissipation of the energy in said energy storing device being such that the energy falls to a first predetermined level in the interval between each predetermined period and falls to a second predetermined energy level upon failure of operation of said first mentioned means for several of said predetermined periods, means responsive to said second energy level for opening said first normally closed switch, a second energy storage device, means responsive to the normal rise and fall of energy in said first mentioned energy storage device during each predetermined period for supplying energy to said second energy storage device, means for continuously dissipating the energy in said second energy storage device, a third normally closed switch, said third normally closed switch connected in said first circuit and means actuated when the energy in said second energy storing device falls below a predetermined minimum for operating said third normally closed switch.

8. A supervisory circuit for use with a burglar alarm system which detects the presence of an intruder by

responding to the disturbance of a standing wave pattern of ultrasonic waves which comprises a first circuit connected to a remote location, said first circuit comprising at least a first normally closed switch and an impedance, a second circuit comprising a second normally closed switch and a normally open switch, said second circuit connected across a portion of said first circuit including said impedance, means operated during a disturbance of the standing wave pattern to close said normally open switch, means for periodically disturbing the standing wave pattern for predetermined periods, means for opening said second normally closed switch during said periods, an energy storing device, means responsive to the operation of said first mentioned means for supplying energy to said energy storing device, means for continuously dissipating the energy in said energy storing device, the rate of dissipation of the energy in said energy storing device being such that the energy falls to a first predetermined level in the interval between each predetermined period and falls to a second predetermined energy level upon failure of operation of said first mentioned means for several of said predetermined periods, means responsive to said second energy level for opening said first normally closed switch, a second energy storage device, means responsive to the normal rise and fall of energy in said first mentioned storage device during each predetermined period for supplying energy to said second energy storage device, means for continuously dissipating the energy in said second energy storage device, a third normally closed switch, said third normally closed switch connected in said first circuit, means responsive to a signal initiated on said first circuit at the remote locations for short circuiting at least part of said impedance, a relay, said last mentioned means being responsive to a second signal initiated at the remote location for opening the short circuit around the impedance and for connecting said relay across at least part of said impedance thereby energizing said relay, means responsive to the energization of said relay for disturbing the standing wave pattern and means also responsive to the energization of said solenoid for short circuiting said second normally closed switch.

9. For an alarm system in which carrier fluctuations are propagated in an enclosure and there modulated by a condition to be detected and in which the modulations are employed to actuate a signal switch to give an alarm, supervisory apparatus for periodically disturbing the propagation of the carrier fluctuations to simulate the condition to be detected and responsive to give a trouble signal if the signal switch is not actuated upon each disturbance, said supervisory apparatus comprising a first circuit, a switch in the first circuit, means in the first circuit actuated by operation of the first circuit switch to disturb the propagation of the carrier fluctuations by the alarm system and thereby simulate the condition to be detected in the enclosure, means associated with the first circuit switch for effecting short interval periodic operation thereof, a second circuit, a switch in the second circuit, a trouble signal device in the second circuit actuatable by operation of said second circuit switch, a third circuit, control tube means in the third circuit having a control electrode and an output which increases with the potential on the control electrode, relay means in the third circuit energized by a predetermined control tube output, said second circuit switch being held unoperated by energizing of the third circuit relay means, a fourth circuit, capacitor means in the fourth circuit having one side connected to the control electrode, by-pass means connected to the said one side of the capacitor means and adapted to dissipate therefrom at a predetermined rate potential thereon, and a switch in the fourth circuit operated by actuation of the signal switch to apply a potential to the said one side of the capacitor means, whereby the second circuit switch is held unoperated and actuation of the trouble signal devices is prevented as long as the signal switch is actuated by each propagation disturbance to periodically operate

the fourth circuit switch and maintain a potential on the capacitor means and on the control electrode.

10. For an alarm system in which carrier fluctuations are propagated in an enclosure from a propagation source and then modulated by a condition to be detected and in which a signal switch is actuated to give an alarm by apparatus which receives the carrier fluctuations and responds to the modulations thereon, supervisory apparatus for periodically disturbing the propagation of the carrier fluctuations to simulate the condition to be detected and responsive to give a trouble signal if the signal switch is not actuated by each disturbance, said supervisory apparatus comprising a first circuit having a switch therein, means in the first circuit connected to the propagation source and actuated by operation of said first circuit switch to disturb the propagation of the carrier fluctuations by said source, said disturbance simulating the condition to be detected and effecting actuation of the signal switch when the alarm system is functioning properly, means associated with the first circuit switch for effecting short interval periodic operation thereof, a second circuit having a switch therein, a trouble signal device in the second circuit actuatable by operation of said second circuit switch, a third circuit, control tube means in the third circuit having a control electrode and an output which increases with increases in potential on the control electrode, relay means in the third circuit energized to hold the second circuit switch unoperated by a predetermined control tube output, a fourth circuit, capacitor means in the fourth circuit having one side connected to the control electrode and to by-pass means adapted to dissipate at a predetermined rate any potential on the said one side of the capacitor means, and a switch in the fourth circuit operated by actuation of the signal switch to apply a potential to the said one side of the capacitor means, said predetermined rate of potential dissipation by the by-pass means being selected so that if the fourth circuit switch is not actuated upon each periodic propagation disturbance to replenish the potential on the said one side of the capacitor means said potential, also appearing on the control electrode, decreases until the control tube output is less than the predetermined output and the second circuit switch is operated to actuate the trouble signal device.

11. For an alarm system in which supersonic fluctuations are propagated into an enclosure from a transmitter source and then modulated by a condition to be detected in the enclosure and in which receiver apparatus adapted to receive the fluctuations responds to the modulations thereon to energize the relay means of a relay operated signal switch and thereby actuate alarm devices, supervisory apparatus for periodically disturbing the propagation of the fluctuations at the transmitter source to simulate the condition to be detected and responsive to give a trouble signal if the signal switch relay means is not energized by each disturbance, said supervisory apparatus comprising a first circuit, a switch in the first circuit, means in the first circuit connected to the transmitter source and actuated by operation of the first circuit switch to disturb the propagation of the fluctuations, said alarm system receiver apparatus being capable of responding to the disturbed fluctuations to energize the signal switch relay means when the alarm system is functioning properly, means associated with the first circuit switch for effecting short interval periodic operation thereof, a second circuit, a switch in the second circuit, a trouble signal device in the second circuit actuatable by operation of said circuit switch, a third circuit, relay means in the third circuit adapted to hold the second circuit switch unoperated when energized by a predetermined current, control tube means in the third circuit having a control electrode adapted to draw said predetermined current through said third circuit relay means when the control electrode is at a predetermined potential, a fourth circuit, capacitor means in the fourth circuit

having one side connected to the control electrode, bypass resistor means connecting the said one side of the capacitor means to a ground point, said by-pass means being adapted to dissipate at a predetermined rate potentials on the said one side of the capacitor means, a switch in the fourth circuit actuated by energizing of the signal switch relay means to apply a potential to the said one side of the capacitor means which exceeds the predetermined potential, said predetermined rate of potential dissipation being selected so that if the fourth circuit switch is not actuated upon each periodic disturbance to replenish the potential on the said one side of the capacitor means, said potential becomes less than said predetermined potential and the second circuit switch operates to actuate the trouble signal device.

12. The combination with an alarm system in which supersonic fluctuations are propagated into an enclosure from transmitter means and then modulated by a condition to be detected in the enclosure and in which receiver means adapted to receive the fluctuations respond to the modulations thereon to actuate alarm devices, of supervisory apparatus for periodically disturbing the normal operation of the transmitter means to cause the fluctuations propagated thereby to resemble fluctuations modulated by the condition to be detected and responsive to give a trouble signal if the receiver means does not respond to the fluctuations resulting from each disturbance, said alarm system having an alarm circuit, an alarm device in the alarm circuit, a signal switch in the alarm circuit operated by response of the receiver means to actuate the alarm device, said supervisory apparatus comprising a first circuit, a switch in the first circuit, means in the first circuit and in the transmitter means actuated by operation of the first circuit switch to briefly disturb the normal operation of the transmitter means and cause the fluctuations propagated thereby to resemble fluctuations modulated by the condition to be detected in the enclosure, said receiver means being capable of responding to fluctuations resulting from said disturbances when the receiver means is functioning properly, means associated with the first circuit switch for effecting short interval periodic operation thereof, a second circuit, a switch in the second circuit, a trouble signal device in the second circuit actuatable by operation of said second circuit switch, a third circuit, relay means in the third circuit adapted to hold the second circuit switch unoperated when energized by a predetermined current, control tube means in the third circuit having a control electrode adapted to draw said predetermined current through said third circuit relay means when the control electrode is at a predetermined potential, a fourth circuit, capacitor means in the fourth circuit having one side connected to the control electrode, by-pass resistor means connected between the said one side of the capacitor means and a point in the fourth circuit which is at a lower potential than the said one side, said by-pass means being adapted to dissipate at a predetermined rate potentials on the said one side of the capacitor means which exceed the potentials at said point, a switch in the fourth circuit actuated by a response of the receiver means which is capable of operating the signal switch to apply a potential to the said one side of the capacitor means which exceeds the predetermined potential, said predetermined rate of potential dissipation by the by-pass means being selected so that if the fourth circuit switch is unactuated by any periodic disturbance the potential on the said one side of the capacitor means becomes less than the predetermined potential before the occurrence of the succeeding periodic disturbance and the second circuit switch operates to actuate the trouble signal device, and said alarm circuit having an additional switch therein operated by the means effecting periodic short interval closing of the first circuit switch to render the alarm device incapable of actuation during the periodic disturbance.

13. For an alarm system in which carrier fluctuations are propagated in an enclosure and there modulated by

a condition to be detected and in which the modulations are employed to actuate a signal switch to give an alarm, supervisory apparatus for periodically changing the character of the propagated fluctuations to simulate the condition to be detected and responsive to give a trouble signal if the signal switch is not actuated upon each periodic change, said supervisory apparatus comprising a first circuit, a switch in the first circuit, means in the first circuit actuated by operation of the first circuit switch to change the character of the propagation fluctuations to simulate the effect on said fluctuations of the condition to be detected in the enclosure, means associated with the first circuit switch for effecting short interval periodic operation thereof, a second circuit, first and second switches in the second circuit, a trouble signal device in the second circuit actuatable by operation of either of said second circuit switches, a third circuit, control tube means in the third circuit having a control electrode and an output which increases with the potential on the control electrode, first and second relay means in the third circuit energized by a predetermined control tube output, said second circuit first switch being held unoperated by energizing of the third circuit first relay means, a fourth circuit, capacitor means in the fourth circuit having one side connected to the control electrode, by-pass means connected to the said one side of the capacitor means and adapted to dissipate therefrom at a predetermined rate any potential thereon, a switch in the fourth circuit operated by actuation of the signal switch to apply potential to the said one side of the capacitor means, a fifth circuit, additional control tube means in the fifth circuit having a control electrode and an output which increases with the potential thereon, relay means in the fifth circuit energized by a predetermined additional control tube output, said second circuit second switch being held unoperated by energizing of the fifth circuit relay means, a sixth circuit, additional capacitor means in the sixth circuit having one side connected

to the control electrode of the additional control tube, additional by-pass means connected to the said one side of the additional capacitor means and adapted to dissipate therefrom at a certain rate any potential thereon, and a switch in the sixth circuit operated between each periodic change by the decay in energization of the third circuit second relay means to apply a potential to the said one side of the additional capacitor means.

14. A supervisory circuit for use with a burglar alarm system which detects the presence of an intruder by responding to a disturbance of a standing wave pattern of ultrasonic waves which comprises a first circuit carrying a predetermined current and including a local circuit portion and a central office circuit portion, said central office circuit portion including an alarm means operated upon variation of said current from said predetermined current, said local circuit portion having a predetermined impedance, a second circuit shunted across said local circuit portion and including a normally closed switch and a normally open switch, signal actuated means operated during a disturbance of the standing wave pattern to close said normally open switch and complete the shunting of said first circuit to vary the current in the central office circuit portion to operate the alarm means, circuit test means associated with said normally closed switch for opening the same during a test to prevent the operation of the alarm means as a result of the test and operative to vary the standing wave pattern to produce a signal operating said signal actuated means there-
30 by closing said normally open switch.
